(57)

CLAIM

The ornamental design for a cannula, as shown and described.

DESCRIPTION

FIG. 1 is a perspective opened view of a cannula, showing the present design;

FIG. 2 is a top opened view of the present design;

FIG. 3 is a bottom opened view of the present design;

FIG. 4 is a left side opened view of the present design;

FIG. 5 is a front opened view of the present design;

FIG. 6 is a rear opened view of the present design; and,

FIG. 7 is a perspective closed view of the cannula of FIG. 1.

The broken lines shown in the figures depict portions of the cannula that form no part of the claimed design.

1 Claim, 7 Drawing Sheets(56)
